UNITED STATES PATENT OFFICE.

JOSEPH P. TUCKER, OF SEATTLE, WASHINGTON.

GARMENT-FASTENER.

1,308,611.

Patented July 1, 1919.

Specification of Letters Patent. Application filed December 18, 1918. Serial No. 267,238.

To all whom it may concern:

Be it known that I, JOSEPH P. TUCKER, citizen of the United States, residing at Seattle, in the county of King and State 5 of Washington, have invented certain new and useful Improvements in Garment-Fasteners, of which the following is a specification.

My invention relates to improvements in 10 garment fasteners.

An important object of the invention is to provide a garment fastener having no spring element or elements, and which is substantially flat when the members thereof are as 15sembled.

A further object of the invention is to provide a device of the above mentioned character, which is simple in construction, inexpensive to manufacture, and highly con 20 venient in use.

Other objects and advantages of the invention will be apparent during the course of the following description.

In the accompanying drawings forming a 25 part of this specification and in which like numerals are employed to designate like parts throughout the same,

Figure 1 is a perspective view of the members of the device, showing the same sepa 30 rated,

Fig. 2 is a central vertical longitudinal section through the device with the members assembled, and,

Fig. 3 is a similar view, showing the mem 35 bers angularly arranged.

In the drawings, wherein for the purpose of illustration is shown a preferred embodiment of my invention, the numeral 1 designates one member of the garment fastener, 40 and 2 designates the coacting member.

The member 1 is formed of a piece of wire or the like, which is bent to provide a transverse head 3, having end portions 4, which lie flat or parallel therewith. The 45 end portions 4 are bent into curved or looped portions 5, providing an eye 6, arranged rearwardly of the transverse head 3, and equidistantly spaced from the ends thereof. The wire extends rearwardly beyond the 50 looped portions 5, in the form of parallel contacting arms 7, forming a shank, disposed at a right angle to the transverse head 3. At their ends, the arms 7 are provided with eyes 8 for attachment to the garment, 55 by sewing or the like.

The coacting member 2 is also formed of

a section of wire or the like, providing a transverse portion or bar 9, which is bent downwardly upon itself at a point equidistantly spaced from the ends thereof for providing a hook or holding projection 10, to enter the eye 6. At its ends, the transverse portion is bent to form substantially vertical loops 11, for the reception of the transverse head 3. The wire is continued beyond the 60 loops 11, in the form of horizontal arms 12, having eyes 13, for attachment to the garment, by means of sewing or the like. At or near the ends of the transverse portion or bar 9 and inwardly of the vertical loops 11, 65 such portion is bent to form approximately horizontal pivot cranks or lateral extensions 14, which are preferably slightly inclined downwardly.

In the operation of the device, the member 75 2 is preferably held in the angular position, as indicated in Fig. 3, and the transverse head 3 inserted through the vertical loops 11, the pivot cranks 14 contacting with the transverse head 3. The holding member or 80 hook 10 is now positioned near and above the eye 6. When the member 2 is swung upwardly to the horizontal position, as shown in Fig. 2, the cranks 14 turning upon the transverse head 3, the holding member 85 or hook 10 will enter the eye 6, and the two members 1 and 2 will be securely locked.

It is to be understood that the form of my invention herewith shown and described is to be taken as a preferred example of the 90 same, and that various changes may be resorted to in the shape, size, and arrangement of parts, without departing from the spirit of my invention, or the scope of the subjoined claims.

Having thus described my invention I 95 claim:

1. A garment fastener of the character described, comprising a member including a transverse head and a longitudinal shank 100 said shank having an eye formed therein near its forward end; and a coacting member comprising a transverse portion provided with a depending holding element to enter the eye, said transverse portion being provided at its ends with substantially vertical loops and inwardly of and near the loops with approximately horizontal pivot cranks; and means to secure the members to the parts of a garment.

2. A garment fastener of the character described, comprising a member formed of a

section of wire which is bent upon itself to provide a transverse head, said section of wire being extended to form a shank arranged at substantially a right angle to the transverse head, said shank having its material bent into loops forming an eye, and its ends bent to form eyes; a coacting member formed of a section of wire providing a transverse portion which is bent down-
wardly upon itself to provide a central depending holding member, the transverse

portion being bent at its ends to provide substantially vertical loops, said transverse portion being further bent to provide approximately horizontal pivot cranks, the material of the transverse member extending beyond the substantially vertical loops to form arms having their ends bent to provide eyes. 15

In testimony whereof I affix my signature. 20

JOSEPH P. TUCKER.
